UNITED STATES PATENT OFFICE.

GEORGE H. GILLIGAN, OF PROVIDENCE, RHODE ISLAND, ASSIGNEE TO U. S. RING TRAVELER COMPANY, OF PROVIDENCE, RHODE ISLAND, A CORPORATION OF RHODE ISLAND.

SPINNING OR TWISTING RING.

Application filed June 16, 1928. Serial No. 285,847.

My invention relates to rings for spinning and twisting frames, and particularly to rings of the type purposed to carry horizontal rather than vertical travelers; that is to say, rings flanged at their tops to present a general I or T shape in transverse section.

The essential objects of my invention are to lubricate both the web and the flange or flanges of the ring; to prevent both excoriation of the web, and wear or friction of the horns of the traveler; and to effect these ends in such a manner as to avoid any obstruction to the horns of the traveler in its movement over the ring.

To the above ends essentially my invention consists in such parts, and in such combinations of parts, as fall within the scope of the appended claims.

20 In the accompanying drawings which form a part of this specification,

Figure 1 is a plan view of a ring for spinning and twisting frames embodying my invention together with a traveler of the horizontal type mounted thereon,

Figure 2, a section of ring taken on line 2—2 of Figure 1, and

Figure 3, a similar section of a modified form of ring.

30 Like reference numerals indicate like parts throughout the views.

As herein shown the web portion 5 of my ring is provided near its lower end with an external annular shoulder 6 to form an abutment for the ring rail, but this shoulder may be omitted if desired, and the shape of the vertical web in cross section is immaterial. The web is integral at its top with the medial line of the flange 7. This flange 40 comprises a flat central portion 8, and flat laterally extending or wing portions 9 all in the same horizontal plane. Interior, annular, transversely swelled or curved shoulders 11 form traveler bearings.

45 In the top of the central portion 8 of the flange is an annular channel 13, of trunconical cross section in this instance, from the bottom portion of which at intervals extend downwardly inclined passages 14, each 50 terminating at the junction of the web with a shoulder 11. The passages are directed successively to opposite sides of the web.

The traveler 18 for which this ring is purposed is of the horizontal or bow type comprising the arched or semicylindrical body 19 and flat horizontal horns 20. The portion 19 does not in operation contact with the flange, but the bearing is substantially, on the horns 20, upon the shoulders 11, and incidentally upon the web 5.

55 In Figure 3 is shown a ring of the same character as that in Figures 1 and 2, but of the reversible type. In this alternative embodiment of my invention the second flange 22 is identical with the flange 7, and is provided with the channel 13 and passages 14 already described.

In employing my ring a liquid lubricant, either independently or in a saturated material, is placed in the channel 13 and exudes 70 through the passages 14. The location of the discharge ends of the passages is such that the emerging liquid not only lubricates the vertical faces of the web which is exposed by the extremities of the traveler horns 75 20; but also flows downwardly and outwardly over the shoulders 11, thus lubricating the latter and preventing friction and wear upon the contacting bearing surfaces 80 of the horns. The direction of the lubricating passages to both sides of the ring protects the web from excessive frictional contact regardless of which horn is engaged therewith. The shoulders 11 further eliminates friction by presenting minimum contacting areas to the horns. A further important function of the shoulders is to keep the horn extremities remote from the passages or openings 14 which would otherwise, in certain tilted positions of the 90 traveler, catch and impede the latter in its annular travel.

85 I claim:—

1. In a spinning or twisting ring of the character described, a web, a flange centrally 95 integral with the web and provided with an annular channel in its top in the vertical plane of the web, and with passages extending from the channel to points adjacent the web at opposite sides of the web.

100 2. In a spinning or twisting ring of the character described, a web, a flange integral with the web provided with an annular channel in its top, a transversely curved

shoulder upon the bottom of the flange, said flange being also provided with a passage extending from the channel to the bottom of the flange.

- 5 3. In a spinning or twisting ring of the character described, a web, a horizontal flange centrally integral with the web provided centrally with an annular channel in its top portion and with downwardly inclined passages extending from the channel to the bottom of the flange adjacent to the web, and bearing means upon the bottom of the flange for spacing traveler horns from the passages.
- 10 4. In a spinning or twisting ring of the

character described, a web, a flat flange comprising a central portion integral with the top and laterally extending wing portions, and depending shoulders upon the wing portions extending from their ends to points 20 adjacent the web, said central portion being provided with an annular channel, and with spaced inclined passages extending in succession from the channel to points intermediate the web and shoulders at opposite 25 sides of the web.

In testimony whereof I have affixed my signature.

GEORGE H. GILLIGAN.
